CLAIM

An ornamental design for a 14-compartment tray, as shown and described.

DESCRIPTION

FIG. 1 is a top isometric view of the 14-compartment tray according to the present invention;

FIG. 2 is a bottom isometric view of the 14-compartment tray in FIG. 1;

FIG. 3 is a right side view of the 14-compartment tray in FIG. 1;

FIG. 4 is a front view of the 14-compartment tray in FIG. 1;

FIG. 5 is a rear view of the 14-compartment tray in FIG. 1;

FIG. 6 is a perspective view of the 14-compartment tray in FIG. 1; and,

FIG. 7 is a cross-sectional of the 14-compartment tray taken along the line "7-7" in FIG. 1.
